UNITED STATES PATENT OFFICE.

WILLIAM H. McCOLM, OF DENVER, COLORADO.

POTATO-SLICING MACHINE.

Application filed August 7, 1925. Serial No. 48,806.

An object of this invention is to provide improved means for slicing vegetables, particularly potatoes.

A further object of this invention is to provide improved means for slicing and splitting the slices of vegetables, particularly potatoes.

A further object of this invention is to provide a slice-splitting assembly or attachment adapted to be used selectively in respect of a slicing machine.

A further object of this invention is to provide an improved machine for preparing potatoes for "French-fries".

A further object of this invention is to provide an improved machine for preparing potatoes for "shoestrings".

My invention consists in the construction, arrangement and combination of elements hereinafter set forth, pointed out in the claims and illustrated by the accompanying drawing, in which—

Figure 1 is an end elevation of the complete machine, dotted lines indicating the location of two splitting assemblies. Figure 2 is a vertical section on the indicated line 2—2 of Figure 1. Figure 3 is an edge view of a fragment of a disc and parts carried thereby on an imaginary line 3—3 of Figure 1, which line is tangent to the disc. Figure 4 is a section on the indicated line 4—4 of Figure 1, of the disc and parts carried thereby only. Figure 5 is a cross-section of a fragment of the disc and parts carried thereby, on the indicated line 5—5 of Figure 4. Figures 3, 4, 5, are drawn to a scale very much enlarged relative to Figures 1 and 2.

In the construction of the machine as shown the numeral 10 designates generally a supporting frame which may be of any suitable size, form and construction. An operating shaft 11 is journaled in any suitable position on the frame 10 and is driven continuously in one direction by any suitable means. A disc 12 of any suitable size and relative thickness is mounted rigidly on one end of and is driven by the shaft 11. Suitable slicing and splitting devices are mounted on and carried by the disc 12 as hereinafter described. A face plate 13 is mounted parallel with and spaced from the outer face of the disc 12 and is formed with a tapering opening at one side of the center of said disc and also is formed with a hopper 14 on its outer face opening in-

wardly through said opening in the plate. The disc 12 is formed with a plurality of radial slots, in this instance two in number, indicated by the dotted outlines of rectangular form in Figure 1. One of the radial slots is shown by dotted lines in Figure 3, and by solid lines in Figures 4 and 5 and is indicated by the numeral 15. A cutting blade 16 is formed with a body portion substantially corresponding in length with a slot 15 and having right-angled arms 17 on its ends and ears 18 at right angles to the extremities of said arms. The arms 17, one of which is shown in Figure 5, extend through a slot 15 from the inner to the outer surface thereof and locate the body of the cutting blade 16 in a plane between the disc 12 and face plate 13. The ears 18 overlap on the inner face of the disc 12 at the ends of the slot 15 and are spaced from said face by elements 19, such as washers or serrated wedges, and bolts 20, 21 are mounted through said ears, spacing elements and discs and have their heads countersunk in the outer face of the disc. The disc is adapted to be rotated clockwise and in relation to such movement the forward margins of the bodies of the cutting blades are beveled on the inside as shown in Figure 4. The long side walls of the slots 15 are beveled inwardly as shown by full lines in Figure 4 and dotted lines in Figure 3. The explanation thus far goes to the slicing machine and in practical use potatoes are fed to the hopper 14 and project through the opening in the face plate into the path of travel of the cutting blade. In their travel, the cutting blades successively cut slices from the potato and discharge through a chute 22 forming a part of the frame. Friction of the cutting knives and gravity feeds the potatoes from the hopper through the opening in the face plate in order that successive slices may be cut therefrom.

A splitting assembly is built up as follows; a pair of end blocks 23, 24, a plurality of spacing blocks 25, a plurality of splitting knives 26, a rod 27, a stabilizing rod 28 and bolts 29, 30 are employed. The assembly of splitting elements fills the slot 15 from end to end and is located between the cutting edge of a blade 16 and adjacent inclined wall of the slot and overlaps in part on the inner face of the disc 12, there being one splitting assembly provided for each slot. Each of the end blocks 23, 24 is formed with a tongue

31 of less width than the block and extending obliquely to the body thereof thereby forming a shoulder 32 adapted to abut the end walls of the slot 15. The spacing blocks 5 25 are preferably rectangular in form and of a width corresponding to the width of the tongues 31 and of the length to extend the full length of said tongues and overlap on and extend across the bodies of the blocks 10 23. The end blocks 23, 24 and the spacing blocks are formed with registering holes adapted to receive the rod 27, which rod is formed as a bolt and is adapted to clamp the assembly together. The spacing blocks 15 25 also are formed with registering holes on a line paralleling the rod 27 and the end blocks 23, 24 are formed with recesses on their inner faces registering with said holes, said holes and recesses being adapted to 20 receive the stabilizing rod 28 and limit and prevent oscillation of elements on said rods 27, the relation of the stabilizing rod to the holes and recesses being indicated by dotted lines in Figure 5. It will be observed that 25 the end blocks 23, 24 are right and left respectively and are placed back toward back as shown in Figure 5, while the spacing blocks are of uniform shape. The splitting knives 26 are formed with longitudinal slots 30 33 open at one end and one arm 34 of the same is of less length than the other arm 35, the latter arm being formed with a cutting edge 36 on its outside margin. The splitting knives 26 are placed between the end blocks 35 23, 24 and spacing blocks 25 in sequence throughout the length of the assembly, and said knives may be so placed and also be removed by longitudinal movement between said blocks in straddling relation to the 40 rods 27, 28. The outer end portion of the arm 35 of each splitting blade 26 extends beyond the outer face of the disc 12 and across the plane of the cutting edge of a cutting blade 16. After the end blocks, 45 spacing blocks, splitting knives and rods are assembled and secured in place and in rigid connection by tightening the rod 27, the entire splitting assembly is mounted on the disc 12 in proper relation to a slot 15 and cutting blade 16 and secured in place by the 50 bolts 29, 30 extending through the end blocks and having their heads countersunk in the outer face of the disc. When the machine is equipped with the splitting assemblies as 55 shown and described and the disc is operated clockwise, as for slicing, the outwardly-projecting end portions of the arms 35 penetrate the potatoes on parallel lines and form arcuate slits therein. The next following 60 slicing blade intersects the arcuate slits and severs strips from the potatoes. The knives

may be so spaced in the splitting assemblies and the cutting blades 16 be so spaced relative to the disc as to vary the cross-section of the strips severed from the potatoes, thus 65 determining the product in respect of shoestrings or French fries. In like manner the spacing of the slicing blades 16 relative to the outer face of the disc 12, through the employment of more or less spacing elements 19, will determine the relative thickness 70 of a slice removed from the potatoes.

I claim as my invention—

1. A potato slicing machine comprising a face plate formed with a feeding hopper, a disc mounted parallel with said plate and formed with radial slots having an orbit coincident with said hopper and a slicing blade mounted on said disc adjacent each slot therein, each slicing blade being spaced 80 from the face of the disc adjacent said plate and formed with arms extending through said slots and ears adapted to be adjustably related to and secured on said disc.

2. In a machine of the character described, a splitting assembly comprising end blocks, spacing blocks, splitting knives mounted between and extending beyond said blocks, an assembling rod extending through said blocks and knives, a stabilizing rod extending through some blocks and through said knives and seated in other said blocks, and means for mounting said assembly in a rotating element.

3. In a machine of the character described, a splitting assembly comprising end blocks, spacing blocks, splitting knives mounted between and extending beyond said blocks, an assembling rod extending through said blocks and knives, a stabilizing rod extending through some of said blocks and through said knives and seated in other said blocks, said knives being longitudinally slotted and open at one end, and means for mounting said assembly in a rotating element.

4. In a machine of the character described, a splitting knife formed with a longitudinal slot open at one end, one arm of said knife being of greater length than the other arm and formed with a cutting edge.

5. In a machine of the character described, a block formed with a tongue oblique to and extending beyond the body of the block, said tongue being of less thickness than the block.

Signed at Denver, in the county of Denver and State of Colorado, this 2nd day of July, 1925.

WILLIAM H. McCOLM.
